HARRY F. HARTMAN, OF PITTSBURGH, PENNSYLVANIA, ASSIGNOR TO WESTINGHOUSE ELECTRIC & MANUFACTURING COMPANY, A CORPORATION OF PENNSYLVANIA

BRUSHHOLDER

Application filed October 11, 1929. Serial No. 398,891.

My invention relates to brushholders for dynamo-electric machines, and it has more particular relation to brushholder fingers and the supporting shafts therethrough, especially in connection with alternating-current railway motors, although it is susceptible, of course, of other uses.

Carbon brushes are preeminently the best for use in the current-collecting devices of dynamo-electric machines and are almost universally used. These brushes must, in general, be pressed down against the commutator cylinder or collector ring by means of a spring-pressed brushholder finger which bears against the top of the brush. The top of the brush may, or may not, be covered with metal.

Heretofore, it has been customary to make the brushholder-finger tips of hard-drawn copper, which was the best known contact material, prior to my present invention, for withstanding the chattering on the top of the carbon brush.

It has long been known that small quantities of tin or other metals, when alloyed with copper, increase the strength of the metal but also very rapidly decrease the conductivity as the quantity of the alloying metal is increased. It has also been known that, when cadmium is utilized as the alloying metal, it gives practically the same increase in strength without nearly as great a decrease in the conductivity. It has not been known, however, that a cadmium-copper alloy is far less affected by arcing; that is, that it will not be eaten away and chipped off when subjected to the tiny arcs and chattering which are likely to occur at the point of contact between the brushholder finger and the brush. A long investigation of means for increasing the life of brushholder fingers or of the finger tips therefor has not revealed any better commercially obtainable material than cadmium-copper alloy, which is capable of withstanding the arcing and

pounding to which these fingers are subjected. The alloying of between one-half and one percent of cadmium with substantially pure copper about triples the life of the finger tip, as compared with what it was with hard-drawn copper.

With a brushholder finger tip having such increased life, it becomes practicable to join the finger tips non-removably to the rest of the brushholder finger, and I have found that the cost of the brushholder finger may be reduced more than fifty per cent by casting the same from a light aluminum alloy having a lower melting point than the cadmium-copper finger tip, and causing the stem of the finger tip to so project into the mold as to be surrounded by the aluminum alloy and thus be anchored into place as an integral part of the brushholder finger.

While aluminum alloys, in general, have the property of flowing readily in molding, the alloys of the silicon group are as easy flowing as any, and the particular alloy having about 12% or 13% of silicon, with the rest substantially pure aluminum, (although about one-half of one percent of iron may easily be tolerated), is the strongest of this group of silicon-aluminum alloys, and it has the property of being tough and ductile when hot and quite satisfactory for use in complicated molds, such as brushholder molds, whereas all other metals, when alloyed with aluminum to the extent of 13%, would produce an alloy which would crack on cooling.

After a long and exhaustive investigation, I have standardized upon silicon-aluminum as the best material for my cast brushholder finger and upon this particular 12% or 13% silicon-aluminum alloy which is preferred.

As a further development of my brushholder finger, particularly designed for alternating-current commutator motors for railway service, although it is obviously not limited thereto, I have sought to double the

life of the brushholder fingers heretofore used, and this has necessitated a change in the shaft which supports the brushholder finger. During my investigation, I have developed a special testing machine giving an indication, in 100 hours, of the durability of, for instance, an aluminum-to-bronze bearing having two years life in service. I have found that aluminum brushholder fingers have a tendency to become tight on the shaft, due to the dragging of the aluminum.

After a wide range of investigation, I have standardized upon graphitized micarta as the material for the shaft. Instead of getting twice the life of a bearing utilizing a bronze shaft, for example, which I started out to obtain, my special vibrating-test machine has indicated that the substitution of graphitized micarta for bronze has provided a bearing-life of between seven and eight times that of the aluminum-to-bronze bearing, so far as its bearing qualities are concerned.

The graphitized micarta, which I now utilize for all brushholder shafts, is a graphitized molded-composition product having a cloth base, as will be subsequently described. It gives a longer life of shaft than any metal shaft material that I have ever experimented with for this type of service; it gives and maintains a free movement of shaft, thereby increasing the life of the finger tip and increasing the life of the cast aluminum-alloy portion of the brushholder finger, whereas the bronze shaft for the aluminum finger would get tight, due to dragging of the aluminum, after a certain time; it has a high electrical resistance and is of such nature that any current that may be transmitted from the moving finger will not cause it to pit, thereby eliminating any chance for the finger to freeze or stick to it; and it does not absorb moisture and does not require a finish or plating on the shaft to keep it from rusting, and, therefore, my new graphitized micarta shafts may be readily stocked over a long period of time.

All of the above-mentioned developments have been worked out at very considerable cost, by more or less empirical methods, and I desire to secure patent protection covering these contributions to the art.

In the accompanying drawings,

Figure 1 is a longitudinal sectional view through a complete brushholder embodying my invention, in a form desirable for use in alternating-current railway motors, showing the carbon brush in place, and an outline of the commutator cylinder or slip ring upon which the brush bears, and

Fig. 2 is a sectional view through the hub of the brushholder finger, on a plane indicated by the line II-II in Fig. 1.

The brushholder finger illustrated in the drawings is of the same general type as that shown in a patent of J. V. Dobson No. 1,533,237, granted April 14, 1925, and assigned to the Westinghouse Electric and Manufacturing Company, and my own Patent No. 1,569,367, granted January 12, 1926.

The brushholder 1 supports a carbon brush 2 which bears on a commutator cylinder or other current-collecting cylinder 3.

The brushholder carries a shaft 4 which supports a brushholder finger 5 having an enlarged hub 6 which is mounted for movement around said shaft.

The hub is provided with an annular recess 7 which is open at one end and is adapted to house a helical spring 8. The brushholder finger 5 is provided with a separate finger tip 9 which bears against the top of the brush 2.

As hereinabove described, my finger tip 9 is made of cadmium-copper and is provided with a stem 10 which is embedded in the material of the rest of the brushholder finger which is cast around it. This brushholder finger material is preferably a silicon alloy of aluminum, as already described.

As also mentioned hereinabove, the shaft 4 is made of graphitized micarta. This material is preferably prepared by mixing 10 gallons of bakelite-varnish with 22.5 pounds of graphite. The micarta is then thinned with a solvent, such as a mixture of alcohol and benzol. Cloth, such as cambric or eight-ounce duck, is then passed through a vat containing the resulting mixture. The impregnated cloth is finally dried, wrapped around a mandrel and molded, under heat and pressure, to harden the bakelite.

I claim as my invention:

1. In a brushholder, the combination with a supporting shaft and a helical biasing spring, of a brushholder finger of the type having an enlarged hub mounted for movement around said shaft and having an annular recess open at one end for receiving said helical spring, characterized by the fact that the finger is nearly all of a cast silicon alloy of aluminum and is provided with a finger tip of a cadmium alloy of copper having a stem embedded in said cast alloy of aluminum, and characterized further by the fact that the said shaft is of a graphitized molded-composition product having a cloth base.

2. In a brushholder, the combination with a supporting shaft and a helical biasing spring, of a brushholder finger of the type having an enlarged hub mounted for movement around said shaft and having an annular recess open at one end for receiving said helical spring, characterized by the fact that the finger is nearly all of a cast alloy of aluminum and is provided with a finger tip of a cadmium alloy of copper having a stem embedded in said cast alloy of aluminum.

3. In a brushholder, the combination with a supporting shaft and a helical biasing spring, of a brushholder finger of the type having an enlarged hub mounted for movement around said shaft and having an annular recess open at one end for receiving said helical spring, characterized by the fact that the finger is provided with a finger tip of a cadmium alloy of copper.
10. 4. The combination with a carbon brush for a dynamo-electric machine, of a brushholder for supporting the same and a brushholder finger having a finger tip of a cadmium alloy of copper pressing against the top of said brush.
15. 5. The invention, as specified in claim 4, characterized by the fact that the finger tip has a stem embedded in a brushholder finger material having a lower melting point than said tip material, the brushholder-finger material being substantially rigid at the operating temperatures.
20. 6. The invention, as specified in claim 4, characterized by the fact that the finger comprises a cast silicon alloy of aluminum and that said finger tip has a stem embedded in said cast alloy of aluminum.
25. 7. The invention, as specified in claim 4, characterized by the fact that the finger comprises a cast alloy of aluminum and that said finger tip has a stem embedded in said cast alloy of aluminum.
30. 8. The combination with a carbon brush for a dynamo-electric machine, of a brushholder for supporting the same and a brushholder finger having a finger tip pressing against the top of said brush, characterized by the fact that the finger tip has a stem embedded in a brushholder finger material composed of a light metal alloy.
35. 9. In a brushholder, the combination with a supporting shaft and a helical biasing spring, of a brushholder finger of the type having an enlarged hub mounted for movement around said shaft and having an annular recess open at one end for receiving said helical spring, characterized by the fact that the finger comprises a cast silicon alloy of aluminum.
40. 10. In a brushholder, the combination with a supporting shaft and a helical biasing spring, of a brushholder finger of the type having an enlarged hub mounted for movement around said shaft and having an annular recess open at one end for receiving said helical spring, characterized by the fact that the finger comprises a cast alloy of aluminum and a copper finger-tip partially embedded therein.
45. 11. The combination with a current-collecting brush for a dynamo-electric machine, of a brushholder for supporting the same, a brushholder-finger shaft carried by said brushholder, and a brushholder finger carried by said shaft and pressing against the top of said brush, characterized by the fact that said finger comprises a cast silicon alloy of aluminum.
50. 12. The combination with a current-collecting brush for a dynamo-electric machine, of a brushholder for supporting the same, a brushholder-finger shaft carried by said brushholder, and a brushholder finger carried by said shaft and pressing against the top of said brush, characterized by the fact that said finger comprises a cast silicon alloy of aluminum having approximately 12% of silicon.
55. 13. The combination with a current-collecting brush for a dynamo-electric machine, of a brushholder for supporting the same, a brushholder-finger shaft carried by said brushholder, and a brushholder finger carried by said shaft and pressing against the top of said brush, characterized by the fact that said finger comprises a cast silicon alloy of aluminum, and characterized further by the fact that the said shaft is of a graphitized molded-composition product having a cloth base.
60. 14. The combination with a current-collecting brush for a dynamo-electric machine, of a brushholder for supporting the same, a brushholder-finger shaft carried by said brushholder, a brushholder finger carried by said shaft and pressing against the top of said brush, characterized by the fact that said finger comprises a cast silicon alloy of aluminum, and characterized further by the fact that the said shaft is of a graphitized molded-composition product.
65. 15. The combination with a current-collecting brush for a dynamo-electric machine, of a brushholder for supporting the same, a brushholder-finger shaft carried by said brushholder, and a brushholder finger carried by said shaft and pressing against the top of said brush, characterized by the fact that said finger comprises a cast silicon alloy of aluminum, and characterized further by the fact that the said shaft is of a graphitized fibrous material.
70. 16. The combination with a current-collecting brush for a dynamo-electric machine, of a brushholder for supporting the same, a brushholder-finger shaft carried by said brushholder, and an aluminum-alloy brushholder finger carried by said shaft and pressing against the top of said brush, characterized by the fact that the said shaft is of a graphitized molded-composition product having a cloth base.
75. 17. The combination with a current-collecting brush for a dynamo-electric machine, of a brushholder for supporting the same, a brushholder-finger shaft carried by said brushholder, and an aluminum-alloy brushholder finger carried by said shaft and pressing against the top of said brush, characterized by the fact that the said shaft is of a

graphitized molded-composition product.

18. The combination with a current-collecting brush for a dynamo-electric machine, of a brushholder for supporting the same, 5 a brushholder-finger shaft carried by said brushholder, and an aluminum-alloy brushholder finger carried by said shaft and pressing against the top of said brush, characterized by the fact that the said shaft is 10 of a graphitized fibrous material.

In testimony whereof, I have hereunto subscribed my name this 30th day of September, 1929.

HARRY F. HARTMAN.
